UNITED STATES PATENT OFFICE.

HENRY W. MCCOMBS, OF BOSTON, MASSACHUSETTS.

DRAIN-COCK-OPERATING MECHANISM.

SPECIFICATION forming part of Letters Patent No. 728,491, dated May 19, 1903.

Application filed December 29, 1902. Serial No. 136,935. (No model.)

To all whom it may concern:

Be it known that I, HENRY W. MCCOMBS, a citizen of the United States, and a resident of Boston, in the county of Suffolk and State of Massachusetts, have invented new and useful Improvements in Drain-Cock-Operating Mechanism, of which the following is a specification.

My invention relates to mechanism for draining engine-cylinders of condensation.

In connection with engines, and locomotives in particular, it has been customary to provide each cylinder thereof with a pair of drain-pipes, one at each end of the cylinder, for removing condensation. These two drain-pipes have been controlled by a pair of valves, commonly called "relief-valves," operated in some cases by pistons in supplemental cylinders connected with a source of fluid-pressure by a pair of conduits, one of said conduits communicating with one end of each supplemental cylinder and the other conduit communicating with the other end of the supplemental cylinder. It has been customary also to provide an engineer's valve, located in the cab of the locomotive, for controlling the pair of conduits which connect the supplemental cylinder with the supply of fluid under pressure. By means of this valve the engineer could operate the pistons in the supplemental cylinders at will and through the pistons operate the valves controlling the drain-conduits, so as to open and close them to remove condensation from the cylinders of the engine.

In my Patent No. 651,879, dated June 19, 1900, a cylinder-relief mechanism much the same as that above described is fully shown; but it may be remarked here that heretofore the engineer's valve described has required a voluntary act of the engineer to effect each movement thereof—that is to say, said valve normally occupied an intermediate position with the cylinder cut off from the supply of fluid-pressure—and in order to open the engine-cylinder-relief valves the engineer shifted his valve from its intermediate position in one direction, and to close the engine-cylinder-relief valves the engineer shifted his valve from that extreme position back to and then beyond its intermediate position in the opposite direction, after which he returned

the valve to its intermediate position. Thus it will be seen that the engineer was required to return the engineer's valve to its intermediate closed position from either extreme position, and since a continued pressure in the supplemental cylinders is unnecessary after the pistons thereof have been operated the result of the engineer's neglect or failure to close the valve after opening it for the purpose of operating the supplemental pistons has heretofore been the wastage of the fluid under pressure through its escape past the supplemental pistons or otherwise. In practice this wastage of the fluid under pressure, due to the engineer's failure to close the valve, has been found highly objectionable, particularly when the fluid-pressure is obtained from the engine or main reservoir of the air-brake system of the train.

My invention has for its object to lessen the amount of attention and labor required of the engineer in using systems of the character above described and to make part of the operation of draining the engine cylinder or cylinders automatic, and, moreover, to economize in the use of the fluid under pressure by preventing the wastage of the same, which has heretofore resulted from the neglect or failure of the engineer to close the controlling-valve.

To these ends I combine with a supplemental cylinder and piston a pair of conduits connecting the cylinder with a source of fluid-pressure, a pair of automatically-closing valves, one in each conduit, and a single valve-operating member common to both valves.

In the best form of my invention as herein shown each end of the supplemental cylinder is connected by a separate conduit with a source of fluid-pressure, and a separate valve is provided in each conduit, adapted to be opened manually and to close automatically. By this construction the piston in the supplemental cylinder is moved positively by fluid-pressure in both directions, which, while not essential to all forms of my invention, is best for all practical purposes.

Also in the best form of my invention a single valve-operating member is provided for controlling both valves and by which either valve may be opened independently and to the exclusion of the other and which

is itself operated and returned to normal position by the automatic closing of either valve.

Another feature of my invention resides in a duplex valve of novel construction, which is particularly well fitted for controlling the supply of fluid-pressure to a supplemental cylinder. As herein shown, this valve comprises a casing provided with two conduits, in each of which is a valve and a valve-operating member mounted on the casing and adapted to control both of said valves. Although this valve, as stated, is particularly adapted for the use above described, yet I do not limit this feature of my invention in this respect, for it will be obvious that a duplex valve so constructed is a new article of manufacture and may be used separately in other connections.

Other features of my invention are herein-
20 after pointed out.

In the accompanying drawings, which show one embodiment of my invention, Figure 1 is a view, partly in elevation and partly in perspective, of a cylinder-relief mechanism embodying the invention. Fig. 2 is a central longitudinal section of the valve hereinafter described. Fig. 3 is a section on line 3-3 of Fig. 2. Fig. 4 is a section on line 4-4 of Fig. 2.

Referring to the drawings, 1 represents the cylinder of an engine—a locomotive, for instance. At each end of the cylinder 1 the usual drain or relief conduits 2, 2 are provided, through which the cylinder 1 is at intervals drained or relieved of condensation. 35 The conduits 2, 2 are each normally closed by a valve 3, whose stem 4 projects into a supplemental cylinder 5, within which is arranged a tapered piston 6. The piston 6 may be reciprocated in its cylinder 5 by admitting fluid 40 under pressure into said cylinder alternately through pipes 7 and 8. The pipes 7 and 8 may be connected with the air-brake system of the train either directly or through an auxiliary reservoir, or, if desired, they may be connected with the boiler of the locomotive. When fluid under pressure is admitted 45 to the cylinders at their inner or proximate ends through pipes 8, each piston is driven to the opposite end of its cylinder, and the 50 action of the tapered part of each piston is to lift and open its valve 3, past which the condensation from cylinder 1 passes to and through a port 9, from which it discharges onto the ground. To close valves 3, fluid under 55 pressure is admitted to cylinders 5 through pipe 7, and each piston 6 is driven back to the opposite end of its cylinder, which allows valves 3 to close onto their seats. The above-described construction is substantially the 60 same as in my Patent No. 651,878, dated June 19, 1900, which may be referred to for an explanation of details.

Each of the pipes 7 and 8 communicates with one of two ports 10, provided in a valve- 65 casing 11. Each port 10 is normally closed by a valve 12, held on its seat by a spring 13, compressed between its valve 12 and a re-

movable plug 14. The stem 16 of each valve 12 extends through a stuffing-box 17 to the outside of casing 11, with the outer end of 70 each stem in the path of one of two oppositely-disposed arms 18 on a valve-operating member 19. The valve-operating member 19 is herein shown as a lever, pivoted at 20 to a lug on the casing 11, and by grasping the 75 free end thereof the operator may rock it in either direction and operate either valve to the exclusion of the other, springs 13 returning the valves automatically to their seats and member 19 to its normal position when 80 released.

Each port 10 communicates through ports 21 and 22 in casing 11 with one end of a pipe 23, through which fluid under pressure is 85 conveyed to ports 10.

When cylinder 1 is to be drained of condensation, the operator swings lever 19 to the left, Fig. 1, which opens the valve 12 controlling pipe 8, thus admitting fluid under pressure to one end of each cylinder 5 and 90 driving pistons 6 to the opposite ends of said cylinders. This opens valves 3 and allows the condensation to escape from the cylinder through ports 9. After having swung lever 19 in the direction above described the operator may release it, and the compressed spring 13 being thereby freed will automatically return its valve onto its seat and lever 19 to its upright normal position with both valves closed.

After the cylinder 1 has been drained of condensation the operator swings lever 19 in the opposite direction, which opens the valve 12 of pipe 7, thus admitting fluid-pressure to cylinders 5 upon the opposite side of each 105 piston 6, which returns each piston to its first position and closes valve 3. The release of lever 19 by the operator frees the compressed spring of the last-opened valve and allows it to automatically close said valve and return 110 lever 19 to its intermediate normal position with all of the parts of the mechanism back into normal position.

In each end of each supplemental cylinder 5 I provide a small exhaust hole or port *e*, 115 which is constantly open. The ports *e* are so small that they do not sensibly affect the operation of the pistons 6 when fluid under pressure is admitted from the conduit 7 or 8; but as soon as pressure is cut off these ports 120 reduce the internal pressure to that of the atmosphere.

By means of a socket 23' the casing 11 may be fastened in place within the cab of the locomotive to any suitable support. 125

My improved mechanism does not require as much attention and labor of the engineer as has heretofore been the case, for by simply striking lever 19 on one side, and thereby momentarily opening one valve, the supplemental pistons are moved in one direction, and by simply striking the lever 19 on the opposite side, and thereby momentarily opening the other valve, the supplemental pistons 130

may be returned to their first position, the closing of the valves automatically returning the lever to its normal intermediate position. It will also be clear that the automatic closing of the valves prevents wastage, which has heretofore resulted from the engineer's failure to close the controlling-valve, which failure was not due so much, perhaps, to neglect of duty as to the engineer's attention being required for others of the many duties required of him.

What I claim is—

1. The combination with a supplemental cylinder and piston, of a pair of independent conduits connecting the cylinder with a source of fluid-pressure, a pair of independent automatically-closing admission-valves, one in each conduit, and a single valve-operating member common to both valves.
2. The combination with the supplemental cylinder and piston, of a pair of independent conduits connecting the cylinder with a source of fluid-pressure, a pair of independent automatically-closing admission-valves

one in each conduit, and a single valve-operating member common to both valves, by which either valve may be opened independently and to the exclusion of the other, and which is itself returned to normal position by the automatic closing of either valve.

3. The combination, with the supplemental cylinder and piston, of a pair of independent conduits connecting the cylinder with a source of fluid-pressure, a pair of independent admission-valves one in each conduit, a pair of springs one for operating each valve, and a valve-operating member common to both valves by which either valve may be opened independently and to the exclusion of the other, and which is itself returned to normal position by the closing of either valve by its spring.

Signed by me at Boston this 20th day of December, 1902.

HENRY W. MCCOMBS.
